UNITED STATES PATENT OFFICE.

NIELS P. B. ELLEGAARD, OF PETALUMA, CALIFORNIA.

EGG-CRATE.

1,200,716.

Specification of Letters Patent. Patented Oct. 10, 1916.

Application filed January 27, 1916. Serial No. 74,640.

To all whom it may concern:

Be it known that I, NIELS P. B. ELLEGAARD, a citizen of Denmark, residing at Petaluma, in the county of Sonoma and State of California, have invented certain new and useful Improvements in Egg-Crates; and I do declare the following to be a full, clear, and exact description of the invention, such as will enable others skilled in the art to which it appertains to make and use the same.

This invention relates to improvements in crates which are primarily intended for shipping eggs, and has for its principal object to provide a simply constructed device of this character which can be very inexpensively manufactured, yet one which will be very efficient.

Another object of the invention is to provide a crate having an extremely simple and improved means for holding the cover in place without the use of nails, hasps, or other similar locking means.

With the above and other objects in view, my invention resides in the novel features of construction, and the combination and arrangement of parts which will be hereinafter more particularly described and claimed and shown in the drawings wherein:

Figure 1 represents a top plan view of my improved crate; Fig. 2 is a side elevation thereof; Figs. 3 and 4 are central vertical longitudinal sections showing several steps in removing the cover or closure from the crate; Fig. 5 is a transverse section taken on the line 5-5 of Fig. 2; Fig. 6 is a detail vertical section taken on the line 6-6 of Fig. 1; Fig. 7 is a perspective view of the closure removed; and Fig. 8 is a similar view of the movable end of the leaf spring latch.

In the accompanying illustrations, I have shown my improved crate as comprising a body or receptacle 1 in which the eggs or other articles to be shipped are disposed and suitably packed. This receptacle may be of any preferred size or shape, but preferably of a size similar to the ordinary egg crate in which the card board partitions for the eggs are used.

The receptacle 1 is provided with a suitable closure 2 which has its ends disposed under the inverted U-shaped members 3 at the opposite ends of said receptacle. Each of the members 3 is formed from a single piece of strap metal bent into U-shape, and secured by its arms 4 to the opposite sides 5 of the body by nails 6 or other fastening

members. As shown, each member 3 is disposed directly over the ends 7 of the body 1, and spaced thereabove a distance slightly greater than the thickness of the closure in order that the ends thereof may freely slide between the tops 3' of the members 3 and the upper edges of the ends 7. The tops 3' of the members are preferably supported in their middle by the spacing blocks 8 which rest on the upper edges of the ends 7.

Each end of the closure 2 is slotted as shown at 9 to receive said spacing blocks 8. This closure is substantially the length of the box or body 1 and in placing the same in position thereon, one end thereof is inserted beneath one of the members 3 and slid in the same direction until the opposite end clears the other member 3 when said closure is moved in the reverse direction until the last mentioned end is flush with the corresponding end 7 of the receptacle.

In order to limit the movement of the closure in one direction, a cleat 10 is secured thereto transversely thereof at a point spaced from one end substantially a distance equal to the width of one of the members 3. In order to limit the movement in the reverse direction, I provide a leaf spring latch 11 secured by one end thereto, its opposite end being provided with a depending stop 12 which, when the cover or closure is in position on the receptacle 1, will contact with the inner edge of the top 3' of one of the members 3. This stop is disposed at the opposite end of the closure from the cleat 10 and contacts therewith to securely hold the closure in operative position. This stop 12 is preferably formed by depressing the spring 11 adjacent its free end, said free end being also provided with a handle formed by bending the extreme outer portion thereof upon the intermediate portion as shown at 13 in the drawing.

An additional cleat 14 is secured to the closure transversely thereof adjacent the free end of the latch 11, and overlies the same. This cleat 14 is grooved on its lower side as shown at 15 to receive said spring 11, and in this groove is also disposed an expansion helical spring 16 which bears against said spring 11 and the top of its seat in the groove in order that said leaf spring will be held in engagement with the closure, and therefore in engagement with one of the members 3.

In placing the cover or closure in posi-

tion, one end is slid beneath the top of one of the members 3, the free end of the spring 11 sliding over said member, and said closure is moved in this direction a sufficient extent to allow the opposite end to clear the other member 3. When the closure has been disposed in this position, it is moved in the reverse direction until the cleat 10 contacts with one of the members 3, when the stop 12 will spring into engagement with the edge of the other member. In order to remove the closure, the free end of the spring 11 is raised in order to release the stop 12, and the movements as above described are reversed as shown in Figs. 3 and 4.

From the preceding description, it is obvious that I have invented a crate having a very simple means for attaching its cover thereto and securely holding the same thereon. It is also evident that such a crate as this can be manufactured very cheaply, yet at the same time with sufficient strength to withstand a great deal of rough usage and will last a considerable length of time, the locking means for the cover being practically indestructible.

In the foregoing I have described certain details of construction for producing probably the best results, and in the drawings I have shown such details, but it will be evident that I need not be limited thereto otherwise than to the extent to which the appended claims limit me.

I claim as my invention:

35 1. In a device of the class described comprising a receptacle, an inverted U-shaped member at each end thereof, the tops of said members being spaced above said ends, a closure disposed under said members, a cleat 40 carried by said closure and spaced from the ends thereof, said cleat abutting one of said members to limit the movement of the closure in one direction, a latch carried by the closure and having one end abutting the 45 other member to prevent movement of said closure in the reverse direction, an additional cleat overlying said latch and having a groove therein to receive the same, and an

expansion spring interposed between the top of said groove and said latch.

2. In a device of the class described comprising a receptacle, an inverted U-shaped member at each end thereof, the tops of said members being spaced above said ends, a closure disposed under said members, a cleat 55 carried by said closure and spaced from the ends thereof, said cleat abutting one of said members to limit the movement of the closure in one direction, and a leaf spring secured at one end to the closure, its other end being bent upon itself to form a handle, said spring adjacent its free end being depressed to form a stop to contact with the other member to prevent movement of said closure in the reverse direction.

3. In a device of the class described, a receptacle, a pair of inverted U-shaped members each formed from a single metal strap and secured by the arms thereof to the sides of the receptacle, one being adjacent each 70 end thereof, the tops of the members being disposed over and spaced above the ends thereof, a closure disposed under said members, a cleat carried by said closure and spaced from the ends thereof, said cleat 75 abutting one of said members to limit the movement of the closure in one direction, a leaf spring secured by one end to the closure, its other end being bent upon itself to form a handle, said spring adjacent its free 80 end being depressed to form a stop to contact with the other member to prevent movement of said closure in the reverse direction, an additional cleat overlying said spring and having a groove therein to receive the 85 same, and an expansion spring interposed between the top of said groove and said leaf spring.

In testimony whereof I have hereunto set my hand in presence of two subscribing witnesses.

NIELS P. B. ELLEGAARD.
